TO ALL WHOM IT MAY CONCERN:

Be it known that I, DANIEL W. PEPPER, of the city and county of Philadelphia, State of Pennsylvania, have invented or produced a new and original Design for a Tinman's Stove; and I do hereby declare that the accompanying drawing, and the following explanation thereof, form a full, clear, and exact description of the said design.

A is the body of the stove, having in front a projection, *a*, inclined at the end for the reception of a cover, *b*. At the rear of the body is a curved pipe, *d*, and in front, below the projection *a*, a curved cover, *e*, for the ash-pit, the whole being supported on legs *f*.

In testimony whereof, I have signed my name to this specification in the presence of two subscribing witnesses.
